IGOR S. BOBROVSKY, OF ROCHESTER, NEW YORK, ASSIGNOR, BY MESNE ASSIGNMENTS,
TO UNITED REPRODUCERS CORPORATION, A CORPORATION OF NEW JERSEY

ART OF ASSEMBLING LOUD-SPEAKERS

Application filed February 20, 1928. Serial No. 255,532.

This invention relates to a method and tool for assembling loud speaker diaphragms upon a face plate, and more particularly to a method and tool for assembling or mounting diaphragms of the type shown in my copending application entitled "Diaphragm mounting for loud speakers," Serial Number 203,956, filed July 7th, 1927, upon a face plate of the type therein shown. In assembling such a diaphragm upon a face plate in the past, it has been proposed to utilize adhesives or other fastening means such as holding rings, clamps or the like, for maintaining the edge of the diaphragm in desired space relation with the face plate. These arrangements have not proved entirely satisfactory, since the use of adhesives provides a rigid connection, which may be undesirable in case of warping or other deformations of the face plate during transportation or in use, and the use of clamping rings, screws, and the like, is subject to the same objection; and is also undesirable since the time required to assemble the diaphragm upon its face plate is objectionable, particularly when it is desired to carry on the assembly of such devices on a quantity production basis. The diaphragm mounting of the type shown and described in my copending application above referred to, is designed to permit a self adjusting connection between the edge of the diaphragm and the face plate, which will permit the rim to creep upon the face plate, thereby eliminating excessive tension upon the edge of the diaphragm. It is somewhat difficult, however, to carry on the assembly operation with such a mounting, if the assembling is done by hand, and particularly when the assembly is carried on a quantity production basis.

It is an object of this invention to provide a method and a tool for facilitating and greatly speeding up the process of assembling and mounting of diaphragms of the type described.

It is a further object of this invention to provide a relatively inexpensive tool which may be utilized in mounting such diaphragms and by which the method, accord-

ing to my invention, may be carried out in such a manner that the diaphragms may be quickly and easily mounted in the desired position.

Still further objects and advantages of my invention will be apparent from the specification.

The features of novelty which I believe to be characteristic of my invention are set forth with particularity in the appended claims. My invention itself, however, both as to its fundamental principles and as to its particular applications, will best be understood by reference to the specification and accompanying drawing, in which:

Figure 1 is a sectional view of a face plate with a diaphragm mounted thereon;

Figure 2 is a sectional view of a diaphragm before mounting;

Figure 3 is an edge view of a face plate, partly broken away;

Figure 4 is a sectional view of the tool according to my invention just prior to the bending operation; and

Figure 5 is a detailed sectional view, after completion of the bending operation.

The diaphragms of the type to which my invention has particular application, are provided with a flexible edge which may be formed, for example, by gluing an annulus of soft and freely flexible and inelastic material, such as kid, to the periphery of the diaphragm. The face plate, upon which such diaphragms are to be mounted, is provided with an opening corresponding approximately in size to the size of the diaphragm, which opening is provided with an outwardly projecting flange; preferably, although not necessarily, this flange is outwardly flared, and the annulus has a width somewhat greater than the maximum width of the flange, whereby the overlap portion of the annulus may be bent inwardly around the flange, and secured in position by a tensioned member, such as an elastic band, string or wire.

In attempting to mount the diaphragm, if the mounting is to be carried on entirely by hand, it is difficult to fold down the annulus and secure it in position by means

of the tensioned member since it is impossible to carry on the folding at all points on the periphery of the flange; when it is attempted to fold the annulus at a plurality of points in succession, it is found to be very difficult to bring each folded portion under the tensioned member without displacing a portion which has already been arranged in proper position. In accordance with my invention, I proceed to carry on the folding operation at all points around the periphery of the annulus simultaneously or substantially so, and after the entire annulus has been folded down simultaneously, I position a tensioned member thereupon. It will thus be seen that the difficulty of properly positioning successive portions of the annulus without disturbing the position of portions already adjusted, is eliminated; and moreover, the time required to mount the diaphragm is substantially no greater than that required to fold down a single portion of the annulus and position the tensioned member thereupon in carrying out the mounting operation by hand.

For the purpose of permitting the folding to be done at all points on the periphery of the annulus simultaneously or substantially so, I provide a tool comprising two parts; one, a support or base preferably mounted for rotation about its center and comprising an upper portion adapted to support the diaphragm, and a lower portion adapted to support the face plate in desired space relation therewith; that is to say, in a manner so that the base of the diaphragm lies substantially in the plane of the outer rim of the flange on the face plate, and so that the diaphragm is symmetrically positioned with respect to the opening in the face plate.

The other portion of the tool comprises a top, preferably in the form of an annular ring corresponding in size and shape to the diaphragm and having a downwardly projecting flange or lip extending around the ring, and of somewhat less depth than the height of the flange of the face plate, whereby the top may be brought down upon the base or support when the face plate and diaphragm are in the desired position and the edge or downwardly depending lip carried by the ring will engage the rim at all points around the periphery thereof, and bend or fold it downwardly over the flange on the face plate. The top is also arranged to carry on its outer cylindrical face an expanded tensioned member, such as a rubber band and the downwardly projecting lip is made shorter than the flange, whereby the tensioned member may be pressed downward off the cylindrical carrying face, and will contact and engage the bent portion of the rim, maintaining it in position.

The projecting edge of the leather rim may be grasped by the fingers or by any

suitable device such as a pair of pliers and pulled taut, the rotational mounting of the base facilitating this adjusting process by permitting free rotation of the entire assembly.

In order to permit the tightening process to be carried out in the manner above described and yet to leave a predetermined desired amount of slack in the rim, there may be provided on the support a projecting annular bead and a corresponding annular groove in the top member. In pulling this rim taut, it is apparent that the rim will follow the curve of this bead and when the top is removed and the face plate with its attached diaphragm lifted from the base or support, the desired and predetermined amount of slack will be present in the rim.

Referring now more particularly to Figure 1, 10 designates generically a face plate of any suitable material, such as metal or wood, having an opening therein defined by an outwardly projecting flange 11: in case the face plate is of metal, the flange 11 may be formed integral with the face plate by turning in a portion thereof, and preferably the flange 11 is slightly flared outwardly, so as to prevent accidental displacement of the mount.

The diaphragm itself comprises a central portion 12, such as a cone, to which is secured a flexible annulus 13, such as soft kid. The outer portion of the annulus 13 is folded downwardly over the flange 11, and secured in position by means of a tensioned member or members, which may comprise a rubber band 14, supplemented if desired, by one or more turns of string or wire 15, suitably secured; for permitting the driving of the diaphragm from the apex, there may be utilized a metal cap "C" attached thereto.

Referring now more particularly to Figure 2, I have shown the form of diaphragm before mounting, in which it will be observed that the rim 13 is attached to the periphery of the diaphragm 12 and extends outwardly therefrom.

Referring now more particularly to Figure 4, the assembling tool comprises a base or support 20, provided with a locating cylindrical ring 24 of approximately the diameter of the opening of the face plate 10 to permit of the face plate 10 being placed thereon and supported in the proper position. The base 20 is preferably rotatably mounted upon a suitable bench or table 22 carrying a bearing, diagrammatically shown as 21, by means of which the support 20 may be rotated with respect to the bench 22. The inner portion 23 of the support 20 is provided of a size and shape arranged to engage the inside of the diaphragm 12 and support it concentrically with respect to the face plate 10, and preferably with the periphery of the diaphragm 12 in the

plane of the edge of the flange 11. For the purpose of permitting the folding or bending of the rim to be carried on at all points around the edge thereof simultaneously, the top comprises an annular ring 25, preferably having a conical inner face 26 arranged to engage the diaphragm 12; the annular ring 25 is provided with an outer cylindrical face 29 extending downwardly below the bottom surface 27 of the annular ring 25, and having a diameter just sufficient to permit the top to be moved downwardly to the position shown in Figure 5 with the diaphragm in position. The lower edge or lip of the member 29 engages the outwardly extending annulus 13 and bends it downwardly over the edge of flange 11 all around the periphery thereof simultaneously. After the top has been forced down, it takes the position shown in Figure 5, and at this point the tension member 14, which has previously been stretched and placed upon the outside of the cylindrical face 29, is pushed downwardly until it passes off the lower edge thereof, whereupon it contracts and engages the bent portion of the annulus 13 with sufficient frictional contact to prevent the same from working out of the desired position when the top is removed. After the top is removed, the face plate and diaphragm may then be removed from the support, after which a supplementary tension member, such as string 15, may be passed over the bent portion of the rim 13 and secured in position.

In case it is desired that the rim 13 be slack as shown, an annular bead 30 may be provided upon the upper portion 23 of the support and a corresponding annular groove 28 may be provided in the lower face of the annular ring 25 of the top. It will be noted that when the top is moved to full engagement as shown in Figure 5, the conical face 26 thereof engages the diaphragm 12 holding it firmly in position, so that the periphery of the annulus 13 may be grasped and pulled taut without danger of deforming or distorting the diaphragm 12, as would be likely to happen if the diaphragm were not supported. It will be seen, also, that the engagement of groove 28 and bead 30 takes up a certain amount of material of the annulus 13, and that even though the annulus be pulled taut, as above described, when the assembly is removed from the support, the desired amount of slack will exist in the rim 13. It will be apparent that the amount of slack may be increased by increasing the height and width of the bead 30 and that the amount of slack introduced may be decreased by decreasing the height and width of said bead, and that if it is desired to eliminate any slack in the complete assembly, the bead 30 and the groove 28 may be omitted.

For the purpose of facilitating the handling of the tool, the annular portion 25 may be provided with an arched handle 31 secured thereto as by suitable screws 32.

It will thus be apparent that I have provided a method and a tool for facilitating the assembly of diaphragms in the manner described, and that while I have shown my invention as particularly applied to the assembly of conical diaphragms having a flexible annulus or rim, it is apparent that my invention may be applied to the assembling of other types of diaphragms as well; and the saving of time in assembling the diaphragms according to my invention, is so great as compared with the prior methods involving the use of glue, holding rings, etc., that the number of operators required for this phase of operations in the assembling of loud speakers, is reduced to a fraction of those formerly necessary.

While I have shown and described certain preferred forms of my invention, it will be apparent that modifications and changes may be made without departing from the spirit and scope of my invention, as will be understood by those skilled in the art.

I claim:

1. A tool for mounting a diaphragm having a flexible edge, upon a plate having an opening therein and having an outwardly extending projection adjacent said opening, against which said edge is to be mounted, said tool comprising a base for supporting said diaphragm and said plate in desired space relation, and a top arranged to engage said edge and bend it over said projection.

2. A tool for mounting a diaphragm having a flexible edge, upon a plate having an opening therein and having an outwardly extending projection adjacent said opening, against which said edge is to be mounted, said tool comprising a base for supporting said diaphragm and said plate in desired space relation, and a top arranged to engage said edge and bend it over said projection, said top being arranged to carry thereon an expanded tension member releasable to retain said edge in bent position.

3. A tool for mounting a diaphragm having a flexible edge, upon a plate having an opening therein and having an outwardly extending projection adjacent said opening, against which said edge is to be mounted, said tool comprising a base for supporting said diaphragm and said plate in desired space relation, and a top arranged to engage said edge and bend it over said projection, said base and said top being so shaped as to leave said edge slack between said diaphragm and said plate after mounting.

4. A tool for mounting a diaphragm having a flexible edge, upon a plate having an opening therein and having an outwardly extending projection adjacent said opening

- against which said edge is to be mounted, said tool comprising a base for supporting said diaphragm and said plate in desired space relation and a top arranged to engage said edge and bend it over said projection, said top having a face for carrying thereon an expanded tension member releasable to retain said edge in bent position and the depth of said face being less than the depth of overlap of said edge upon said projection, whereby lateral displacement of said tension member permits it to contract upon the overlapped portion of said edge to maintain said edge yieldably in position upon said projection.
- 15 5. A tool for mounting a diaphragm having a flexible edge, upon a plate having an opening therein and having an outwardly extending projection adjacent said opening, against which said edge is to be mounted, said tool comprising a base for supporting said diaphragm and said plate in desired space relation and a top having an annular portion arranged to engage the inner portion 20 of said rim, and a downwardly extending portion positioned around said annular portion and arranged to engage the outer portion of said rim and bend it over said projection, upon movement of said top into engagement with said base.
- 25 30 Signed at Rochester in the county of Monroe and State of New York this 15th day of February A. D. 1928.
